(12) **United States Design Patent** (10) **Patent No.:** **US D1,058,595 S**
(45) **Date of Patent:** **** Jan. 21, 2025**

(54) **DISPLAY SCREEN WITH ANIMATED GRAPHICAL USER INTERFACE**

Primary Examiner — John M Otte

(71) Applicant: **SHENZHEN TCL NEW TECHNOLOGY CO., LTD.**, Shenzhen (CN)

(57)

CLAIM

(72) Inventor: **Rui Feng**, Shenzhen (CN)

The ornamental design for a display screen with animated graphical user interface as shown and described.

(***) Term: **15 Years**

(21) Appl. No.: **35/518,280**

DESCRIPTION

(22) Filed: **Aug. 1, 2023**

1.1: Front, first image in a sequence

(80) **Hague Agreement Data**

Int. Filing Date: **Aug. 1, 2023**
Int. Reg. No.: **DM/231116**
Int. Reg. Date: **Aug. 1, 2023**
Int. Reg. Pub. Date: **Sep. 8, 2023**

1.2: Front, second image in a sequence

1.3: Front, third image in a sequence

2.1: Front, first image in a sequence

2.2: Front, second image in a sequence

2.3: Front, third image in a sequence

3.1: Front, first image in a sequence

3.2: Front, second image in a sequence

3.3: Front, third image in a sequence

4.1: Front, first image in a sequence

4.2: Front, second image in a sequence

4.3: Front, third image in a sequence
